UNITED STATES PATENT OFFICE.

ORLANDO E. KELLUM AND SIDNEY A. MURDOCK, OF LOS ANGELES, CALIFORNIA;
SAID MURDOCK ASSIGNOR TO SAID KELLUM.

PHONOGRAPH-DRIVING MECHANISM.

1,346,376.

Specification of Letters Patent. Patented July 13, 1920.

Application filed July 31, 1917. Serial No. 183,707.

To all whom it may concern:

Be it known that we, ORLANDO E. KELLUM and SIDNEY A. MURDOCK, citizens of the United States, residing at Los Angeles, 5 in the county of Los Angeles, State of California, have invented new and useful Improvements in Phonograph-Driving Mechanism, of which the following is a specification.

This invention relates to continuous phonographs and the like; being in the nature of an improvement upon that mechanism shown, described and claimed in application Serial No. 824,909, filed November 15, 1915 by O. E. Kellum. In said application Kellum describes generally a means for making a phonograph or a kinetograph or the like operate continuously; so that a phonograph or kinetograph performance 20 can be carried on indefinitely without any time limit as is now necessarily the case. In this present application we describe an improved form of mechanism as applied to a phonograph; but it will be understood 25 that we do not limit the mechanism to such specific use. It is an object of this present invention to provide an improved form of mechanism for causing continuous operation of a phonograph, or a machine for making 30 or reproducing records; and it is an object of this invention to provide such mechanism in simplified form. In the former application mechanisms are described which are operated and controlled electrically. It is one 35 of the objects of this present invention to provide a form of mechanism entirely mechanical in its nature, capable of being easily made and economically manufactured and so designed and constructed as to be 40 simple in operation and as to have long wearing qualities. It is also an object to provide such a mechanism as can be made in compact form—to provide for continuity 45 of phonograph or other operation without having to have a large, complicated or bulky mechanism.

As broadly explained in said prior application, this invention achieves continuity of a phonograph operation by using a plurality 50 of record tables or carriers, and operating them in series, one after the other; this is done by utilizing a starting mechanism which is controlled by the mechanism then running; that is, controlled either from or 55 by a constantly running motor or shaft, or

controlled from or by the record then being operated. For instance, in a typical construction, as explained in said application, there may be two record tables and a constantly running motor adapted to be connected to either of the tables; and a starting motor adapted to be connected to either of the tables; said starting motor being of such a character as to be capable of synchronous operation and control. The connections between the constantly running motor and the starting motor, and the record tables, are automatically controlled (electrically in that case); so that the operation is substantially this: That, just before one 60 record is finished, the next record is brought up to speed by the starting motor; and then it is connected to a constantly running motor. All of these operations take place in proper predetermined synchronism, so that 65 when the subsequent record is running at full speed, it is then running in proper continuity relation to the preceding record.

The general scheme of operation is the same in the machine of the present invention. However, we prefer to employ purely mechanical means. We employ a pair of record tables adapted to be driven from a constantly running motor or a constantly running shaft. We employ a constantly operated control mechanism; and this control mechanism actuates connective media which put the two record tables alternately into and out of operation. These connective media, controlled by the control mechanism, 80 include not only the means for operating the record tables at normal speed but also include the means for bringing the record tables at normal speed, at the same time keeping the tables in perfect synchronism. 85 The control mechanism starts the connective media in actuation; once these connective media are started in actuation, it then operates automatically to first bring the record up to normal speed and then thereafter to 90 rotate that record at the normal speed until the control mechanism again actuates the connective media to cause the record to stop. As will be seen from the following detailed description, all of these operations take 95 place in such relation to each other that the record tables and records are kept and operated in a certain definite relation to each other. Thus, after these records have once been made in that certain definite relation, 100 105 110

then the mechanism will cause them to be always properly reproduced. In fact, the mechanism we are now about to explain is, broadly speaking, as much for the making 5 of records as it is for their reproduction.

We now proceed to a detailed description 10 of a preferred form of mechanism embodying our invention; and for this purpose we have reference to the accompanying drawings in which—

Figure 1 is a longitudinal side elevation of the mechanism; Fig. 2 is a plan section taken as indicated by line 2—2 on Fig. 1; Fig. 3 is an enlarged detail vertical section 15 taken as indicated by line 3—3 on Fig. 2; Fig. 4 is a detail section taken on line 4—4 on Fig. 3; Fig. 5 is a detail section taken as indicated on line 5—5 on Fig. 3; Fig. 6 is a similar view showing the parts in another position (hereinafter explained); Fig. 20 7 is a plan section taken as indicated by line 7—7 on Fig. 1, showing the parts in the position shown in Figs. 1, 2, 3, etc.; Fig. 8 is a view similar to Fig. 7 showing the parts 25 in another position; Fig. 9 is a further enlarged detail section as indicated by lines 9—9 on Figs. 2 and 7; Fig. 10 is an enlarged detail section taken as indicated by lines 10—10 on Figs. 2 and 3; and Fig. 11 is a 30 small plan of the machine.

Referring first more particularly to Figs. 1 and 2 we explain that our preferred form of mechanism may be mounted within or upon any suitable frame work 20, above 35 which we place the two record tables 21 which carry the consecutive records 22. These records 22 may be registered upon the tables by pins 23 passing through apertures of the records, or the records may be registered in any other suitable manner. The 40 tables are mounted on table shafts 24. Adjacent each of these table shafts there is a connective medium or driving mechanism M through the medium of which the two record 45 tables are started and driven. Located preferably centrally between these two driving mechanisms we place the control mechanism “C.” The whole machine may be driven from any suitable source of power, as from 50 a constantly running electric motor. Such a motor may drive onto the gear 30 on the shaft 31 mounted in bearings 32; and this shaft 31 is connected by gears 33 and 34 with a shaft 35 which, in the description of 55 this specific mechanism, we shall hereinafter term “the constantly running shaft.” Each of the driving mechanisms and the control mechanism is driven from this constantly running shaft 35. In this particular machine 60 a commutator mechanism is provided at 36, comprising a rotating drum 37 mounted upon the shaft 31 and carrying contacts 38; and a series of contact fingers 39. This commutator mechanism is designed to control the motor which actuates a kinetograph 65

in synchronism with this phonograph; the control and actuation system being substantially as is described in Patent No. 1027658 issued May 28, 1912 to O. E. Kellum.

We shall now first explain the driving 70 mechanisms; of which there are two and one being shown in detail in Figs. 3 and 10. Near each table shaft 24 we mount a vertical driving shaft 40. This driving shaft rotates intermittently. A sleeve 41 is rotatively 75 mounted upon the driving shaft 40 and this sleeve carries a spiral gear 42 which meshes with a spiral gear 43 upon shaft 35. Sleeve 41 is constantly driven in the direction indicated in the various views; and this sleeve 80 41 carries an arm 44, having a driving lug 45 at its outer end. Immediately above the upper end of the sleeve and above the arm 44 there is a member 46 rigidly mounted upon the shaft 40. This member 46 is in 85 the nature of an arm which extends on both sides of the shaft, and at one end carries a pivot pin 47 on which a clutch arm 48 is pivotally mounted. This clutch arm 48 is of the shape shown in Fig. 7 and carries a 90 roller 49 at one end. A small tension spring 50 is connected between the other end of the clutch arm and the member 46, tending at all times to throw the roller 49 outwardly 95 away from the shaft 40. The roller carrying end of the clutch arm carries also a downwardly projecting driving lug 51 adapted to be thrown into the path of the driving lug 45, so that the lug 45 may drive the lug 51, and thus, through the medium 100 of member 48, drive member 46 and the shaft 40. These parts are shown in driving engagement at the right hand side of Fig. 7, and shown out of driving engagement at the left hand side in Fig. 7. The roller 49 105 travels upon an interior circular track 52 formed in a stationary plate 53. This stationary plate 53 may be supported in any suitable manner. The frame of the machine is preferably made of top and bottom plates 110 20 and vertical spacing rods 20^a and the plates 53 may be supported upon these rods 20^a. Now the inner circular track 52 is continuous except for a short open space or break which is filled by a segmental gate 115 54 pivoted at 55. This gate 54 is opened and closed—thrown between the positions shown at the right and left in Fig. 8—by the control mechanism C. The action of the control mechanism will be hereinafter explained:

Shaft 40 extends on up to an upper bearing 60. A driving gear 61 is mounted upon a block 62 slidable upon the shaft 40; and the block 62 is rotatively connected with the 125 member 46 by means of a pin 63 mounted in the member 46; the block 62 being vertically slidable on the pin. The block 62 and gear 61 have two definite positions upon the shaft 40, being shown in their upper position in 130

Fig. 3. A small spring pressed plunger 64, in the block 62, enters a notch 65 in shaft 40 and releasably holds the gear 61 in its upper position. However, a certain pressure downwardly upon the gear and block will force the plunger 64 out of the notch 65 and then the plunger will enter an inclined notch 66, and the action of the spring pressed plunger upon this inclined notch, and the weight of the gear and block, will cause the gear to move immediately to its lowermost position. This position is one in which the driving gear 61 meshes with a pinion 67 on table shaft 24. Immediately above the driving gear 61, and connected thereto by the sleeve or hub 70, we mount the starting driving gear 71. This starting driving gear is of variable pitch radius, its circumference being preferably on a spiral as is best shown in Figs. 5 and 6. When the gears are in their uppermost position (the gear 71 moves vertically with the gear 61) the gear 71 meshes with a similar gear 72 mounted upon the table shaft 24. When these gears are in mesh, and when the table shaft 24 and the driving mechanism M is standing at rest, the gears 71 and 72 normally stand in the position illustrated in Figs. 2 and 5. This is a position corresponding to the position of the parts shown at the left in Fig. 7. The driving mechanism is stopped by the roller 49 entering the opening made by the gate 54 when the gate is thrown to the position shown in Fig. 7; the roller 49 striking the shoulder 52^a thus exposed by the outward movement of the gate. In this position of the parts a small beveled faced lug 73 on the upper end of the hub 70 has just passed a stationary beveled faced lug 74 which is mounted upon the bearing 60. These lugs having just passed each other, when the mechanism comes to rest, the gears 61 and 71 may then be raised to the position shown in Fig. 3. This is done, at present, by a manual operation. In the present form of machine it makes for simplicity to accomplish this operation manually. But the invention is not limited to such an operation. We provide a handle at 75 mounted upon a pivot shaft at 76, and from this pivot shaft a pair of rods 77 extend beneath the gear 61. These rods 77 are normally held down by a small spring 78. Pressing down on handle 75 raises the rods 77 against the gear and raises the gears to the position shown in Fig. 3.

In the position of rest of the driving mechanism and shaft 40, the table shaft 24 and table 21 are in a certain definite position, such as the position shown at the left in Fig. 11. This certain definite relation is maintained between the shaft 40 and shaft 24 for the reason that the connection between the two shafts is never entirely broken. It will be noted that the minimum radius of

the gear 72 is the same as the radius of the driving pinion 67. These two gears 72 and 67 are set upon a sleeve 80 and are fixed in position relative to each other, and to the shaft 24. One of the teeth 67^a of gear 67 is 70 continued on upwardly along the sleeve 80 and may register with one of the teeth 72^a of the gear 72. When the parts are in their position of rest, this long tooth 67^a is always in mesh with the teeth of gear 61; so that the 75 gear 61 may be moved vertically without losing its proper mesh relation to the gear 67. This mesh relation is shown in Fig. 4.

In order to clearly explain this driving mechanism we shall now explain its operation before proceeding to an explanation of the control mechanism. We refer now particularly to the showing at the left hand side of Fig. 7, etc. The driving arm 44 and lug 45 constantly rotate; and, when the 80 table is at rest, the gate 54 is standing in the position shown in Fig. 7, with the roller 49 in the position there shown, and the lug 52^a out of the path of lug 54. At the time it is wished to start the table the control mechanism closes the gate 54 and thereby throws the lug 52^a into the path of driving lug 45. In the next revolution the lug 45 will pick up the lug 52^a and begin to drive it. Through the medium of the driving connections, hereinbefore explained, the gears 61 and 71 are started in revolution. In the position shown in Figs. 2 and 5, it will be seen that the gears 71 and 72 are in mesh at the minimum radius of gear 71 and the 85 maximum radius of gear 72, so that the shaft 24 is started slowly. As these gears 71 and 72 revolve, the gear ratio changes so that, when the gears have turned through approximately a whole revolution, then the 90 maximum radius part of gear 71 is in mesh with the minimum radius part of the gear 72. These two gears are duplicates, with equal numbers of teeth, so that, although the gear ratio changes during each revolution, they will make revolution for revolution with each other. This being the case, when the table shaft 24 has made approximately a whole revolution, and when the single tooth 67^a has been carried around approximately again to the position shown in Fig. 5, then this single tooth 67^a will again accurately throw into mesh with the teeth of gear 61. The ratio between gears 67 and 61 is 1 to 4; and the gears 71 and 72 are made 95 so that after approximately a revolution of the shaft 24, the single tooth 67^a will throw accurately into mesh with the gear 61 at exactly the same point where it previously meshed with that gear at rest. When the 100 parts reach the position shown in Fig. 6, then the rotating lug 73 strikes the stationary lug 74; and during the subsequent rotation of the parts from the position shown in Fig. 6 to the position shown 105

in Fig. 5, these lugs interact to throw the gears 61 and 71 down to their lower positions. The gear 61 then slips into mesh with the gear 67, while gear 71 slips out of mesh with gear 72. The single tooth 67^a rotates into mesh with gear 61 just as the gear 71 leaves gear 72. At this time the shaft 24 is being driven at a speed four times that of shaft 40; and the meshing of the gears 61 and 67 then causes this four-to-one drive to proceed until the gate 54 is again opened. When this occurs, the roller 49 strikes shoulder 52^a and the parts are stopped again in the position shown in Figs. 2, 4 and 5. In this position the gears 61 and 71 may be moved upwardly while the gear 61 is in mesh with the single tooth 67^a; and this meshing keeps the gears 71 and 72 in fixed relation, so that the gear 71 will slip into mesh with gear 72 in exactly its proper relation.

It will now be seen that the table shaft 24 is always in a fixed relation to the driving shaft 40. This is true even though the table shaft at one time makes a whole revolution for a whole revolution of the driving shaft and then thereafter makes four revolutions for every revolution of the driving shaft. It is the function of the driving mechanism to start the table from a certain definite position, bring it up to speed, and then allow the table to be stopped in a certain definite position. It is the function of the control mechanism to so control the driving mechanism as to cause it to rotate the table through a certain definite number of revolutions, no more, and no less. This is effected by closing and opening the gate 54 at certain definite times. For instance, the control mechanism closes the gate 54 during a certain revolution of the driving lug 45; that is, at any time in that revolution after the driving lug has passed lug 51 and before it reaches that lug again. Having thus closed the gate, the driving mechanism operation begins when the driving lug 45 reaches the lug 51. After a certain definite number of revolutions of the lug 51, then, at some time after the roller 49 has passed the shoulder 52^a and before it passes that shoulder again, the gate 54 is opened; and the driving mechanism comes to a stop. It will be seen that by this system of operation the control mechanism need only to be so accurate as to cause the closing and opening of the gate within a certain definite time period represented approximately by a revolution of the driving lug 45. The driving lug 45 travels at about 20 revolutions per minute; so that the control mechanism has very nearly three seconds time period in which the control operation may be effected. The gears 42 and 43 are of one to one ratio; the constantly running shaft 35 rotating at a speed of 20 revolutions per minute. The control mechanism

shaft 90 is driven through the medium of worm gears 91 and 92 from the shaft 35 at a ratio one to one hundred thirty-six; so that the control shaft 90 makes, in this case, a complete revolution in 408 seconds. One revolution of the control shaft 90, and of the control cam 93, causes each of the driving mechanisms M to go through a complete cycle. That is, a period of 408 seconds elapses between successive startings or stoppings of either of the record tables. This particular time period is only selected because one-half of that time period, 204 seconds, is approximately the time period of some standard records. But this time period may be changed by changing the ratio of gears 91 and 92; for instance, the time period for each record may be about six minutes. Of course, it will be understood, and is more fully hereinafter explained, that the actual sound reproduction from each record extends somewhat over this exact time period; the sound reproduction on each record overlaps the sound reproduction on the other record at both ends. This is done by causing each record to rotate a little over one half of the complete period of the control mechanism, and stand still a little less than one half. This is fully explained hereinafter. The control cam 93 is of a peculiar configuration, and its construction and operation are best explained by reference to Figs. 7, 8 and 9. The cam has an outer track consisting of a circular part 94 which extends through approximately half the circumference of the cam. At the back end of this part 94 (the revolution is in the direction indicated) there is a diagonal surface 95 leading inwardly to a circular surface 96 which then extends on around to a sharp shoulder 97 which then drops outwardly directly to the beginning end of the circular surface 94. This shoulder 97 is preferably made on a circumference whose center, when the cam is approximately in the position shown in Fig. 7, is on the pivot 55. The inner track of the cam has a large circular surface 94^a which parallels surface 94 of the outer track through a part of its length. At the rear end of the surface 94^a, and approximately opposite the rear end of surface 94, the inner track has a sharp drop-off shoulder 97^a, formed on a circumference whose center is at 55 (at the right) when the parts reach the position shown in Fig. 8. This shoulder 94^a drops inwardly to the inner circular surface 96^a of the track; and this inner circular surface then proceeds around to and parallels the surface 96 of the outer track to a point opposite the shoulder 97; and then the inner track has a diagonal surface 95^a which leads diagonally outwardly to the beginning end of the surface 94^a.

Upon each pivot 55 we pivot a pair of arms, a short arm 100 and a long arm 101. 130

The short arm 100 in each case carries the gate 54; and it is the movement of this short arm that causes the movement of the gate. Each of these arms 100 and 101 has a cam following pin 102 or 103 adapted to follow the cam groove between the inner and outer tracks. We also pivot a pair of arms 104 and 105 on the pivots 55, and between the outer ends of these two arms we 10 place a spring 106 tending to pull the two arms together. These two arms 104 and 105 are mounted between the arms 100 and 101. That is, the arm 101 is uppermost and the arm 100 is lowermost, and the two arms 15 105 and 104 are between. The pin 103, on the uppermost arm 101 extends down past the arms 104 and 105 into the cam groove and thus may strike either arm 104 or 105. The pin 102 on arm 100 not only extends 20 down into the cam groove but also extends upwardly far enough to strike arm 105 but not far enough to strike arm 101. Thus both pins 102 and 103 may engage the inner edges of either of the arms 104 and 105 25 without engaging the other arm 100 or 101.

Suppose now that the parts are in the position shown in Fig. 7. This is the position assumed when the left hand driving mechanism is just about to then stop operation. The left hand gate 54 is open and the right hand gate 54 is closed. The cam 93 is rotating in the direction indicated. A very slight rotation from the position shown in Fig. 7 will bring the shoulder 97 30 to the pin 102 of the left hand mechanism and the pin 102 will immediately drop over the shoulder 97, being urged by the spring 106 which pulls upon the arm 104, and the arm 104 bearing upon the pin 102. This 35 pin 102 is thus urged outwardly to a position against the outer track surface 94. In thus moving, the pin 102 passes under the arm 101. The arm 104 is beneath the arm 105 and the pin 102 extends up far enough 40 to engage the arm 104 and the arm 105 but will pass under the arm 101. The arm 104 is beneath the arm 105 and the pin 102 extends up far enough 45 to engage the arm 104 and the arm 105 but will pass under the arm 101. The arm 104 is beneath the arm 105 and the pin 102 extends up far enough 50 to engage the arm 104 and the arm 105 but will pass under the arm 101. This movement of arm 100 closes the gate 54 and the left hand driving mechanism then starts operation. The two pins 103 and 102 then follow around the cam groove against the surface 94. It will be 55 noted that the pin 103 is held outwardly by the surface 94^a when the pin 102 reaches the shoulder 97. The pin 103 engages the arm 105 and thus puts a tension on spring 106. The difference in length between arms 60 100 and 101 is that necessary to put the pin 103 far enough ahead of pin 102 to cause the described operation to take place. Pin 103 and arm 101 perform merely the functions of putting a tension upon the spring

106 to cause the desired movements of the 65 pin 102 and arm 100.

When the pin 102 of the left hand mechanism drops off the shoulder 97, the shoulder 97^a has not quite reached the pin 102 of the right hand mechanism. In other 70 words, the gate 54 of the left hand mechanism has closed before the gate 54 of the right hand mechanism is opened. A further slight rotation of the control cam brings shoulder 97^a to the pin 102 of the 75 right hand mechanism; and then the pin 102 of the right hand mechanism drops over shoulder 97^a onto circular surface 96^a (see Fig. 8). The pin 103 is already riding on circular surface 96, having been pushed in- 80 wardly by the diagonal surface 95 and having thus put a tension on spring 106, so that spring 106, through the medium of arm 105, moves the pin 102 quickly in- 85 wardly over the shoulder 97^a. The two pins 85 103 and 102 then follow around the groove between the surfaces 96 and 96^a. The dropping of pin 102 over shoulder 97^a causes the opening of gate 54 of the right hand mechanism, causing that mechanism to stop 90 in the manner hereinbefore described. The position of the various parts, when the above described movements have just taken place, is shown in Fig. 8.

The control cam continues to rotate until 95 it has reached a position diametrically opposite to that shown in Fig. 7. When it reaches this position then operations exactly the reverse of those just described will take place. That is, the cam will first cause the 100 arm 100 of the right hand mechanism to be moved outwardly (just as it before caused the arm 100 of the left hand mechanism to be moved outwardly) and will cause the gate 54 of the right hand mechanism to 105 close, starting that mechanism in operation; and then; immediately afterward, it will cause the arm 100 of the left hand mechanism to be moved inwardly (just as before it caused the arm of the right hand mechanism to be moved inwardly) and will thus cause the gate 54 of the left hand mechanism to be opened, causing the left hand mechanism to stop. The right and left hand driving mechanisms will then be in the conditions shown in Fig. 7. The cam 93 continues to rotate until it has again reached the position shown in Fig. 7. Having reached this position, the whole machine has gone through a complete cycle of operations. 115 Each record table has had a period of operation and a period of rest. Each record table is stopped just slightly after the other table is started. This is caused by the positioning of the shoulders 97 and 97^a upon the 120 cam; instead of these shoulders being exactly diametrically opposite, one of them, for instance the shoulder 97^a, is a little be-

hind a position diametrically opposite to the other, 97. Thus, although the actual period of operation of each driving mechanism is slightly greater than the period of 5 inaction (causing the over-lap hereinbefore mentioned) yet the points at which the start and stop actions come are always exactly the same for each of the two mechanisms. Consequently, each of the record tables will 10 make exactly the same number of revolutions each time it is operated, and will then remain at rest during a certain time period, represented by a certain exact number of revolutions. Under these circumstances it 15 is seen that consecutive continuous records may be easily made or reproduced. A record is placed upon one of the tables, which table is in a certain definite position. After the record has come up to speed, the making or 20 reproduction of the record is commenced. During the operation of this record, another record is placed upon the other table, which is then at rest, in its certain definite position. The operation of the moving record 25 is continued to its end; and, just before this record reaches its end, the previously still record has commenced to rotate. As soon as the second record has reached normal speed, and before the first record stops, the operation 30 of making or reproducing the second record has begun. Thus, it will be seen that there may be a short period of overlap in which both records will be taking or reproducing exactly the same sound, in exact 35 synchronism with each other. This synchronous succession of records can be kept up indefinitely. The operator merely places a succeeding record upon the table at rest, and, in this particular form of machine, also 40 presses down upon the handle 75. This, and the removal of the used records from the tables when they come to rest, is all that is required of the operator.

On the control cam we place a cam 110 for 45 controlling the engagement of the needle with the record; in this case illustrated as a means for controlling the engagement of the reproducer needle with the record. This cam 110 has a single depression 111 in its 50 upper edge, into which depression either one of a pair of cam followers 112 may drop. These cam followers are pivoted at 113 and are connected at 114 with a vertically slideable rod 115. The rods 115 are raised by 55 spring 116 and are normally held down by the engagement of the follower 112 with the surface of the cam. When the follower 112 drops into the notch 11, the rod 115 is raised by spring 116. To each of the vertical rods 115 there is connected a horizontal 60 arm or rod 117 (Figs. 2 and 11) which projects horizontally across the record under the sound box 118; and when either of these arms are raised the corresponding sound 65 box is raised and the needle is raised off the

record. The notch 111 is so placed that each cam follower drops into it just before the corresponding record stops and after the other record has attained its normal speed. Notch 111 is of sufficient extent to allow the 70 sound box and needle to be kept in raised position until the record has stopped. Thereafter the follower 112 is again raised by the cam, causing the sound box to be lowered; or causing the arm 117 to be lowered so that the sound box and needle can 75 manually be lowered into proper position in the first groove of the record which is next placed upon the table just stopped. The raising of the sound box and needle in this 80 manner prevents any scratchy noise from the record then being stopped.

Having described a preferred form of our invention, we claim:

1. In combination, a plurality of driving 85 mechanisms each with a driven shaft, a constantly running means connectible to either of said mechanisms, mechanical means in positive coöperation with the driving mechanisms to bring the driven shaft up to 90 speed, and control means to control connection of the driving mechanisms with the constantly running means.

2. In combination, a plurality of driving 95 mechanisms each with a driven shaft, a constantly running means connectible to either of said mechanisms, mechanical means in positive coöperation with the driving mechanisms to bring the driven shaft up to 100 speed, and mechanical control means to control connection of the driving mechanisms with the constantly running means.

3. In combination, a plurality of driving mechanisms each with a driven shaft and including positive means for bringing the 105 shaft up to normal speed and then driving it at normal speed, a constantly running means connectible to either of said mechanisms, and control means to control connection of the driving mechanisms with the constantly running means.

4. In combination, a plurality of driving mechanisms each with a driven shaft and including positive means for bringing the shaft up to normal speed and then driving it 115 at normal speed, a constantly running means connectible to either of said mechanisms, and mechanical control means to control connection of the driving mechanisms with the constantly running means.

5. In combination, a plurality of driving mechanisms each with a driven shaft and each including positive mechanical means for bringing the shaft up to normal speed and then driving it at normal speed, a constantly running means connectible to either driving mechanism, and mechanical control means to control connection of the driving mechanisms with the constantly running means.

6. In combination, a plurality of driving mechanisms each with a driven shaft and each including positive mechanical means for bringing the shaft up to normal speed and then driving it at normal speed, a constantly running means connectible to either driving mechanism, and mechanical control means driven from the constantly running means to control connection of the driving mechanisms with the constantly running means.

7. In combination, a plurality of driving mechanisms each with a driven shaft and each including positive mechanical means for bringing the shaft up to normal speed and then driving it at normal speed, a constantly running means connectible to either driving mechanism, and mechanical control means driven from the constantly running means to control connection of the driving mechanisms with the constantly running means, said control means including a control cam driven constantly from the constantly running means.

25 8. In a device of the character described, a driven shaft, a driving shaft, gearing connection between the two shafts to cause the driven shaft to be driven at a constant speed from the driving shaft, gearing connection between the two shafts to cause the driven shaft to be driven at an increasing speed from the driving shaft, and means to control the operation of said gearing connections.

35 9. In a device of the character described, a driven shaft, a driving shaft, a driving pinion and a variable radius gear on the driven shaft, a driving gear on the driving shaft adapted to mesh with the pinion on the driven shaft, a variable radius gear on the driving shaft adapted to mesh with the variable radius gear on the driven shaft, the gear on said driving shaft being slidably mounted thereon, and means to slide said gears to throw them into and out of mesh with the gears on the driven shafts.

40 10. In a device of the character described, a driven shaft, a driving shaft, a driving pinion and a variable radius gear on the driven shaft, a driving gear on the driving shaft adapted to mesh with the pinion on the driven shaft, a variable radius gear on the driving shaft adapted to mesh with the variable radius gear on the driven shaft, the gear on said driving shaft being slidably mounted thereon, and fixed in relative

rotative relation to each other, means to slide the driving shaft gears into and out of mesh with the gears on the driven shaft, and means to maintain proper rotative relation between the gears on the driven shaft and the gears on the driving shaft during the period of sliding of the gears on the driving shaft.

45 11. In a device of the character described, a driven shaft, a driving shaft, a driving pinion and a variable radius gear on the driven shaft, a driving gear on the driving shaft adapted to mesh with the pinion on the driven shaft, a variable radius gear on the driving shaft adapted to mesh with the variable radius gear on the driven shaft, the gears on said driving shaft being slidably mounted thereon and fixed in relative rotative relation to each other, means to slide the driving shaft gears into and out of mesh with the gears on the driven shaft, and means to maintain proper rotative relation between the gears on the driven shaft and the gears on the driving shaft during the period of sliding of the gears on the driving shaft, said means embodying a single gear tooth extending between the two gears on the driven shaft, and being an extension of one of the teeth of the driving pinion on that shaft.

50 12. In combination, a plurality of driving mechanisms each with a driven shaft and each including mechanical means for bringing the shaft up to normal speed and then driving it at normal speed, a constantly running shaft, clutch means connecting the driving mechanisms to the constantly running shaft and mechanical control means actuating said clutch means.

55 13. In combination, a plurality of driving mechanisms each with a driven shaft and each including mechanical means for bringing the shaft up to normal speed and then driving it at normal speed, a constantly running shaft, clutch means connecting the driving mechanisms to the constantly running shaft and mechanical control means actuating said clutch means, said control means embodying a control cam constantly driven from the constantly running shaft.

In witness that we claim the foregoing we have hereunto subscribed our names.
